FLUID PUMP

Harold J. Le Vesconte, Chicago, Ill., assignor to
 Union Special Machine Company, Chicago, Ill.,
 a corporation of Illinois

Application July 11, 1932, Serial No. 621,971

11 Claims. (Cl. 103—126)

The invention relates to new and useful improvements in fluid pumps, and more particularly to a fluid pump having interengaging impellers.

5 An object of the invention is to provide a fluid pump of the above type with means for intermittently rotating the impellers.

A further object of the invention is to provide a pump of the above type wherein the extent of intermittent movement imparted to the impellers may be varied for varying the transmitting capacity of the pump without varying the speed of the prime mover therefor.

In the drawings—

15 Fig. 1 is a front view of a pump embodying the improvements and showing in particular the operating mechanism therefor;

Fig. 2 is a sectional view on the line 2—2 of Fig. 1;

20 Fig. 3 is a vertical sectional view through the pump at right angles to the axis of rotation of the impellers;

Fig. 4 is a sectional view on the line 4—4 of Fig. 1;

25 Fig. 5 is a sectional view on the line 5—5 of Fig. 1;

Fig. 6 is a perspective view of one of the impellers;

30 Fig. 7 is a perspective view of one of the clutch members for intermittently rotating the impellers; and

Fig. 8 is an enlarged view partly in side elevation and partly in section showing one of the impellers and its associated operating clutch.

35 The invention is directed to a fluid pump for transmitting fluids and includes a casing provided with a chamber, in which casing is located for rotation impellers which are intermeshed and which divide the chamber so as to provide intake and discharge sections. Each impeller is in the form of an annulus. Located within each impeller is a clutch member. One of the impellers is a driving impeller, and the clutch member therefor is intermittently operated for rotating the impellers. The other im-

40 peller is a driven impeller and the clutch member therein is for the purpose of preventing retrograde movement of the impellers. The clutch member is intermittently oscillated and imparts a continuous intermittent forward movement to the impellers. Means is provided whereby the throw of the clutch may be varied so as to vary the length of the intermittent movement given to the impellers.

45 55 Referring more in detail to the drawings, the

fluid pump includes a central casing member 1 which has a projecting bracket portion 2 formed with bolt holes 3 through which bolts may be placed for securing the pump casing rigidly to a supporting means. Within the central member of the pump casing is a chamber 4, the end walls 5 and 6 of which are circular and curved about centers 7 and 8, respectively. The bottom and top walls of this chamber may be of any suitable shape. Located within this chamber are intermeshing impellers 9 and 10. The impellers are similarly constructed. Each impeller has a central opening 11 therethrough and is provided with intermeshing projections 12 operating as pistons. The projections have the ends thereof curved 15 to conform to the curvature of the end walls 5 and 6 as indicated at 13. When the impellers are placed and intermeshed, the driving impeller 10 contacts with the end wall 6 and the driven impeller 9 contacts with the end wall 5.

20 Located within the driving impeller is a shaft 14 carrying a block 15 which has flat sides indicated at 16 forming the sides of an equilateral triangle. The corners of the triangle are cut away forming curved faces 17. These curved faces conform to the inner curved surface of the impeller annulus. The shaft 14 extends through the impeller 10 and is mounted for rotation in bearings in the pump casing. The pump casing not only includes a central casing member 1, but side casing members 18 and 19. These side casing members contact with the central casing member and are secured together by a bolt 20. The side casing members are provided with bosses in the region of the bearings for the shaft 30 supporting the clutch member. Between the block 15 and the inner surface of the impeller are clutch rollers 21. There is one clutch roller 35 for each flat side of the block. The flat side of the block has a groove 22 formed therein and attached to the block and lying in the groove beneath the roller 21 is a spring 23. This spring is so shaped as to normally hold the roller pressed against the inner face of the impeller.

40 On the end of the shaft 14 is an arm 24 provided with a slot 25. Adjustable in the slot 25 is a stud 26 to which a link 27 is attached. This link is pivoted at 28 to a rock lever 29 which in turn is pivotally mounted at 30. An eccentric strap 31 is pivoted at 32 to a rock lever and cooperates with the eccentric 33 on the shaft 34 which is the prime mover for operating the pump. As this shaft rotates, it will, through the train of mechanism described, oscillate the shaft 14. When the shaft 14 is moved in a clockwise direc- 45 50 55

tion, the roller will be caused to grip the impeller 10 and will impart rotating movements thereto to an extent depending upon the extent of oscillation of the arm 24. When the arm is oscillated in the opposite direction, the clutch is released from the impeller which remains stationary while the clutch is returned for a new gripping hold on the impeller 10. There is a similar clutch 35 with rollers and springs located within the impeller 9. The shaft 36 carrying this clutch is fixed to the end members of the casing by nuts 37 and 38 which serve the double function of preventing the shaft from rotating, and tightly joining the end sections of the casing to the central section thereof.

From the above it will be apparent that the impellers are mounted for intermittent rotation in the casing and have a bearing contact with the curved faces of the casing. They also have a bearing contact with the blocks of the clutch members and at one time the driving impeller moves with the clutch block while at another time it rotates on the clutch block. The driven impeller rotates on the fixed clutch block associated therewith which is stationary and which prevents the impeller from any retrograde movement. This provides a means whereby the impellers are intermittently rotated in a forward direction. By adjusting the stud 26 the extent of movement of the clutch block driving the pump can be varied and this will vary the intermittent movement given to the impellers. The side members of the casing are provided with openings therethrough which are in alinement. A cap nut 40 may be threaded into one of these openings for closing the same, and a pipe 41 attached to the other by a suitable coupling. This pipe may serve as an intake pipe for the pump, in which case the fluid will be drawn into the pump at the lower section of the casing which is divided by the impellers into an intake section and a discharge section. The side members of the casing are also provided with openings, one of which may be closed by cap nut 42 and the pipe 43 attached to the other by a suitable coupling which will serve as a discharge pipe for the discharge side of the pump. These cap nuts 42 are interchanged with the pipes and the upper pipe may be made an intake pipe and the lower one a discharge pipe if the pump is rotated in the opposite direction. The two shafts on which the clutch devices and gears are supported may be turned end for end in the casing, and this will reverse the direction of rotation of the impellers. The operating elements of the pump can be shifted, making the other impeller a driving impeller, or so as to place the operating arm on the other side of the pump. This greatly facilitates the installing of the pump with minor changes in the machine with which it is associated. The pump is simple in construction, consisting of few parts, and even when operated at high speeds the parts are subject to little wear.

The pump is especially adapted for the supplying of oil to a high speed machine such as a sewing machine wherein the prime moving shaft may be rotating from 4,000 to 5,000 R. P. M. One of the problems in a high speed machine is to reduce the supply of a pump to the requirements of the machine. The pump which has just been described may be driven at high speed and the amount of oil delivered reduced to a very small amount, due to the fact that for each rotation of the prime mover a very small movement may be given to the impellers. Furthermore, the ex-

tent of movement given to the impellers may be readily varied without in any way changing the speed of the prime mover, and thus the transmitting capacity of the pump adjusted to suit the demands of the machine. This is accomplished without in any way throttling the pump or loading the same. While the pump is especially adapted for transmitting oil under the conditions stated, it will be understood that it may be used equally as well for other purposes where the amount of fluid transmitted is relatively small and the conditions are such that the prime mover operating the pump is a high speed part.

It is obvious that other forms of intermittently rotating impellers may be used than those described in detail and that the clutches may be otherwise placed relative to the impellers and the casing, and minor changes made in the details of construction without departing from the spirit of the invention as set forth in the appended claims.

Having thus described the invention, what I claim as new and desire to secure by Letters Patent, is—

1. A fluid pump comprising a casing having a pump chamber therein, a rotatable impeller and means cooperating therewith for dividing said chamber into intake and discharge sections, an operating shaft extending through said impeller, clutch means located within the pump chamber for intermittently operating said impeller from said shaft for transmitting fluid from the intake to the discharge side of the chamber, said clutch means and shaft constituting the sole means for rotating said impeller, and means for restraining the impeller from retrograde movement whereby the impeller is driven when said shaft is rotated in one direction and is stationary when said shaft is rotated in the other direction.

2. A fluid pump comprising a casing having a pump chamber therein, a rotatable impeller and means cooperating therewith for dividing said chamber into intake and discharge sections, an operating shaft extending through said impeller, clutch means located within the impeller for intermittently rotating said impeller from said shaft for transmitting fluid from the intake to the discharge side of the chamber, said clutch means and shaft constituting the sole means for rotating said impeller, and means for restraining the impeller from retrograde movement whereby the impeller is driven when said shaft is rotated in one direction and is stationary when said shaft is rotated in the other direction.

3. A fluid pump comprising a casing having a pump chamber therein, a rotatable impeller and means cooperating therewith for dividing said chamber into intake and discharge sections, an operating shaft extending through said impeller, means located within the pump chamber for intermittently operating said impeller from said shaft for transmitting fluid from the intake to the discharge side of the chamber, and devices operating upon said cooperating means for restraining the impeller from retrograde movement.

4. A fluid pump comprising a casing, a pump chamber therein, intermeshing rotatable impellers located within said pump chamber and dividing said chamber into intake and discharge sections, an operating shaft extending through one of said impellers, clutch means located within the pump chamber for intermittently rotating said impellers from said operating shaft for transmitting fluid from the intake to the discharge side of said chamber, said clutch means

- and shaft constituting the sole means for rotating the impellers, and means for restraining the impellers from retrograde movement whereby the impellers are driven when said shaft is rotated in one direction and are stationary when said shaft is rotated in the other direction.
5. A fluid pump comprising a casing, a pump chamber therein, intermeshing rotatable impellers located within said pump chamber and dividing said chamber into intake and discharge sections, an operating shaft extending through one of said impellers, means located within the pump chamber for intermittently rotating said impellers from said operating shaft for transmitting fluid from the intake to the discharge side of said chamber, a stationary shaft extending through the other of said impellers, and means within the pump chamber disposed between said stationary shaft and the impeller associated therewith for restraining said impellers from retrograde movement.
6. A fluid pump comprising a casing having a pump chamber therein, rotatable intermeshing impellers located in said pump chamber and dividing said chamber into intake and discharge sections, an operating shaft extending through the casing and one of said impellers, clutch means located within the impeller associated with the operating shaft for intermittently rotating said impellers from said shaft, said clutch means and shaft constituting the sole means for rotating the impellers, and means for restraining the impellers from retrograde movement whereby the impellers are driven when said shaft is rotated in one direction and are stationary when said shaft is rotated in the other direction.
7. A fluid pump comprising a casing having a pump chamber therein, rotatable intermeshing impellers located in said pump chamber and dividing said chamber into intake and discharge sections, an operating shaft extending through the casing and one of said impellers, means located within the impeller associated with the operating shaft for intermittently rotating said impellers from said shaft, a stationary shaft extending through the other impeller, and means located within said last-named impeller and cooperating with said stationary shaft for restraining the impellers from retrograde movement.
8. A fluid pump comprising a casing, a chamber therein, intermeshing annular impellers contacting with the end walls of the casing and dividing said chamber into intake and discharge sections, a clutch located within one of said impellers for intermittently rotating the same, and a clutch located within the other impeller and cooperating therewith for preventing retrograde movement of said impeller.
9. A fluid pump comprising a casing having a central section and side sections secured thereto and forming a chamber, a shaft mounted in said side sections, an impeller mounted on said shaft and having the ends of the shaft shaped to conform to and contact with the end wall of the casing, a second impeller meshing with the first-named impeller and having its shaft contacting with the opposite end wall of the casing, a shaft on which said second impeller is mounted, means for securing said last-named shaft in a fixed position, a clutch carried by said shaft and cooperating with the impeller mounted thereon for preventing retrograde movement therein, a clutch carried by the first-named shaft and cooperating with the impeller thereon for intermittently rotating the same, and means for oscillating said first-named shaft.
10. A fluid pump comprising a casing having a chamber therein formed with curved end walls, intermeshing annular impellers located in said chamber and contacting with the respective end walls, a shaft extending through one of said impellers and fixed to said casing, a clutch located within said impeller and cooperating with said shaft for preventing retrograde movement of the impeller, a second shaft mounted for oscillation in said casing and extending through the other impeller, a clutch located within said last-named impeller and cooperating with said shaft for intermittently rotating said impellers, an arm carried by said last-named shaft, and means connected to said arm for oscillating the shaft.
11. A fluid pump comprising a casing having a chamber therein formed with curved end walls, intermeshing annular impellers located in said chamber and contacting with the respective end walls, a shaft extending through one of said impellers and fixed to said casing, a clutch located within said impeller and cooperating with said shaft for preventing retrograde movement of the impeller, a second shaft mounted for oscillation in said casing and extending through the other impeller, a clutch located within said last-named impeller and cooperating with said shaft for intermittently rotating said impellers, an arm carried by said last-named shaft, means connected to said arm for oscillating the shaft, and means whereby the extent of movement imparted to said arm may be varied.
